UNITED STATES PATENT OFFICE

CARL STEFFEN, JR., OF VIENNA, AUSTRIA

PROCESS FOR OBTAINING TRICALCIUM SACCHARATE RICH IN SUGAR AND POOR IN LIME AND OF A VERY HIGH DEGREE OF PURITY

Application filed April 27, 1926, Serial No. 105,011, and in Austria May 18, 1925.

This invention relates to a process for obtaining tricalcium saccharate rich in sugar and poor in lime and of a very high degree of purity.

5 It is known that molasses sugar is obtained by various extraction processes wherein the sugar is precipitated with calcium oxide as an insoluble tricalcium saccharate. The tricalcium saccharate suspended in the liquid 10 is brought to a higher concentration by filtration through filter presses, so that the saccharate filtered off still has a water content of about 70%, and in this water is still to be found the same percentage of non-sugar elements as was present in the precipitation liquid. The process therefore does not succeed 15 in completely separating the sugar from the non-sugar elements, but there always remains a part of the non-sugar elements in the water 20 content of the saccharate. In order now partly to remove from the saccharate the quantities of remaining non-sugar elements, or in order to obtain from the outset as low a content as possible of non-sugar products in the 25 water remaining in the saccharate cake, various methods have been proposed, of which however none has led to practical success.

It has been found that if from 1½ to 3 times the quantity of the sugar content of a 30 cold low-percentage (0.8-2%) sugar solution (dilute juices, sweet washings, waste liquids or molasses), is introduced in the form of separated tricalcium saccharate and mashed into said solution, said tricalcium saccharate decomposes only in part and the lime 35 liberated by the decomposition combines immediately with the sugar of said sugar solution to form a soluble sugar lime compound, whilst the remainder of the tricalcium saccharate remains completely undecomposed. If finely powdered lime is now added to this 40 mixture, the soluble sugar lime compound present in the mixture is precipitated by the lime as an insoluble sugar lime compound. The saccharate thus obtained is separated by 45 pressing in filter presses for the purpose of increasing the concentration. This saccharate has the same composition as regards the relative proportions of sugar and lime, 50 as that obtained by treating an ordinary sugar

solution with lime and is found to be a tricalcium saccharate rich in sugar and poor in lime and of very high purity, the coefficient of purity being 97 to 98.

A second way of carrying out the invention 55 consists herein, that a tricalcium saccharate, which is obtained from molasses, is mashed with lime water and the mashed saccharate is added to a low percentage cold sugar solution. The lime set free by the partial decomposition of the tricalcium saccharate, which has resulted from the mashing with lime water, combines with the sugar of the low percentage sugar solution to form a soluble sugar lime compound. Fresh quantities of powdered lime are added to this saccharate 60 mashed in the sugar solution for further precipitation. The result is identical with that of the first method.

A further method of carrying out the process 70 consists in a combination of one of the processes hereinbefore described with a known combined precipitation and purifying process for the treatment of sugar lime.

According to the said known process an 75 impure sugar solution of a high concentration (from 5 to 7% sugar) is precipitated to form tricalcium saccharate and the liquid containing the latter is passed into a filter press until the pressure rises from 1½ to 2 atmospheres, 80 whereupon the cake obtained is washed with a liquid containing tricalcium saccharate which liquid is produced by precipitating with lime a low percentage sugar solution (2%) from molasses, or a low grade syrup, which consequently has a much lower non-sugar content. By this means the high non-sugar content of the tricalcium saccharate cake, first obtained, 85 is displaced and a tricalcium saccharate of a higher degree of purity is obtained.

In both of the above described methods according to the present invention, there is added to an approximately 0.8 per cent sugar solution (preferably dilute juices), about 2% sugar, and mashed in the form of tricalcium 90 saccharate such as mashed sugar lime, and subsequently fresh quantities of powdered lime are added for precipitating the sugar still present. This precipitation liquid so formed has a non-sugar content of about 100

0.31% and, in accordance with the present invention, is used as the washing liquid in the filter press in carrying out the said known combined precipitation and purifying process. The quantity of the said washing liquid of high purity is three to three and a half times the quantity of the contents of the press and is pressed in the filter press till a pressure of 4-5 atm. is reached. Then the liquid from the first precipitation, which is of high non-sugar content is substituted by the liquid of the second precipitation which is poor in non-sugar content. In this manner saccharates of purity co-efficients 97 to 98 are obtained. 15 In this operation an amount of about 25% of the washed saccharates obtained is returned into the precipitation operation, for washing purposes, whilst the other 75% are led away into the separating station of the 20 factory.

The economic result of the invention lies in the production of saccharate of very high degree of purity, and in which the consumption of lime is the same as with the normal 25 precipitation. The achievement of high purities is of great importance for the factory operation, since the purity is not impaired, but is increased, by the introduction of the saccharate into the dilute juice. Particularly 30 in the manufacture of white sugar is it of great importance to manufacture saccharates of high purity, because, in order to produce sugar of quality, juices of light colour are necessary. The saccharate of low purity 35 contains however large quantities of colouring matter, whereby the juices in the factory become very dark, from which products of good quality can be prepared only with difficulty. A further advantage consists herein, 40 that this process permits a higher concentration of the added liquid of the first precipitation, whereby firstly the sugar losses are decreased in consequence of the quantities of waste lye being diminished and secondly 45 waste lyes of higher concentration are obtained, which makes a lye evaporation more profitable.

The drawing shows diagrammatically by way of example one form of construction of an apparatus for carrying out the process.

From the container L_2 solution flows through the pipe a , and from the molasses container W molasses pass through the pipe b , into the precipitating apparatus F_1 , so that the added liquid has a sugar content of about 6 to 6.5%. This added liquid is subjected to a normal precipitation process, for which purpose the pump T_1 sucks the liquid to be precipitated through the pipe c and forces it 50 through the cooler K_1 into the container S_1 in which finely divided powdered lime is continuously strewn through the lime supplying apparatus M_1 on the flowing precipitation liquid. The liquid supplied flows from the 55 container S_1 into the precipitating appara-

tus F_1 from which the precipitation liquid again flows through the pump T_1 , through the cooler K_1 , into the container S_1 , into which powdered lime is again fed. This cycle is repeated until the necessary tricalcium saccharate is formed, whereupon the precipitation operation is terminated. This is the formerly known precipitation operation. 70

The liquid containing the tricalcium saccharate is then sucked away by the pump P_1 through the pipe c_1 and is forced through the pipe c_2 into the filter press A_1 . The solution flowing away from the filter press is led away through the pipe d into the sewer, or into a solution vaporizer if used. The tricalcium saccharate separated in the press A_1 is discharged into the masher B_1 into which, in addition, through the pipe f_1 , diluted cold juice (syrup or molasses) of 1 to 2% sugar content from the collecting container D is 80 added for mashing. The mashed saccharate is forced by the pump P_4 from the masher B_1 and the pipe e_1 through the pipe e_2 into the container R provided with a stirring apparatus. In the second precipitation apparatus water and dilute juice (syrup or molasses) are deposited to form a 1½ to 2% sugar solution in the collecting vessel F_2 . Hereupon the pump T_2 is put in operation to suck the initial liquid from the collecting vessel F_2 and the pipe h and to force it through the cooler K_2 into the container S_2 . In addition, the mashed saccharate obtained in the first process is allowed to flow from the container R through the pipe g into the container S_2 . The mixture flows off from the container S_2 into the collecting vessel F_2 , from which the pump T_2 forces this liquid again into the container S_2 . This cycle is 90 repeated until the mashed saccharate in the mash is fed to the precipitation apparatus. So much saccharate is added to the starting liquid that the quantity of sugar in the saccharate corresponds to from one and a half to three times the quantity of sugar of the starting liquid. When the introduction of this mashed saccharate is completed fresh quantities of finely powdered lime are supplied through the lime delivery apparatus M_2 to the circulating precipitation liquid, 100 and this is continued until the precipitation liquid becomes precipitated so that it contains only approximately 0.5% sugar in dissolved state. Herewith the second precipitation operation is completed. After completion of the operation the liquid containing the tricalcium saccharate is sucked away by the pump P_2 through the pipe h_1 and is forced through the pipe h_2 into the press A_2 . The solution running off from this press is led away through the pipe m into the container L_1 and is forced by the pump P_3 through the pipe n into the container L_2 . This solution serves again as a starting liquid 110 for a first precipitation process. The sac- 120

125

charate filtered off in the filter press A_2 , arrives in the masher B_2 , from which the saccharate is led away through the pipe s into the separating station of the factory. The 5 saccharate thus obtained has a purity coefficient of from 97 to 98. The pipe f_2 serves for conveying lime water to the dilute juice in the elements F_2 , K_2 and S_2 in order to further dilute the juice and to render it 10 slightly alkaline.

A second form of execution of the process consists herein, that instead of a dilute sugar solution lime water is used in the masher B_1 for the mashing operation. The operation 15 is otherwise identical with that of the first method.

What I claim is:

1. Process for obtaining tricalcium saccharate rich in sugar and poor in lime and 20 of a very high co-efficient of purity, comprising mashing saccharate with a cold solution of low sugar content in such a manner that from one and a half times to three times the amount of sugar is supplied in the form of 25 separated tricalcium saccharate to the sugar contained in said sugar solution, said saccharate having been separated from a molasses solution in a preceding normal precipitating process, and finally adding lime to the mixture 30 in order to precipitate the calcium saccharate dissolved in the mixture.

2. The process according to claim 1 in which the tricalcium saccharate is mashed with lime water and the mixture obtained 35 is added to said low percentage cold sugar solution.

In testimony whereof I affix my signature.
CARL STEFFEN, JUNIOR.
